UNITED STATES PATENT OFFICE

111,714

DESIGN FOR AN AIRPLANE LANDING WHEEL POSITION INDICATOR

Charles Hilaire Henri Rodanet, Neuilly-sur-Seine, France, assignor to Societe Anonyme: Jaeger-Aviation, Levallois-Perret, Seine, France

Application August 24, 1937, Serial No. 71,298
In France March 24, 1937

Term of patent 7 years

To all whom it may concern:

Be it known that I, Charles Hilaire Henri Rodanet, a citizen of the Republic of France, residing at 23 Villa Madrid, Neuilly-sur-Seine (Seine), France, have invented a new, original, and ornamental Design for an Airplane Landing Wheel Position Indicator, of which the following is a specification, reference being had to the accompanying drawing, forming a part thereof.

Fig. 1 is a front elevational view of an airplane landing wheel position indicator showing my new design.

Fig. 2 is a front perspective view thereof;

Fig. 3 is a top plan view thereof, and

Fig. 4 is a rear perspective view thereof.

The design is characterized by a rectangular outline having a substantially round panel within the edges occupied by four lamps spaced to form the corners of an imaginary erect rectangle, and a pair of indicator drums spaced apart along a common horizontal axis so that each drum is located between an upper and a lower lamp upon its respective side within the outline of said round panel.

I claim:

The ornamental design for an airplane landing wheel position indicator as shown and described.

CHARLES HILAIRE HENRI RODANET.
